LOCK NUT

George Tillman Sheley, Indianapolis, Ind.

Application May 22, 1939, Serial No. 274,950

2 Claims. (Cl. 151—36)

The object of my invention is to provide an improved nut-locking washer of such character as to be readily and cheaply manufactured, easily placed, and of such character that, upon removal of a superimposed nut, it will not slip upon its base.

The accompanying drawing illustrates my invention:

Fig. 1 is a plan of a washer embodying my invention; and

Fig. 2 a side elevation of the washer in conjunction with a base, a threaded bolt, and a superimposed unit in a position of advancement on its threaded bolt, just engaging the washer to stress the washer axially.

In the drawing 10 indicates a tempered and springy main body which is a radially split annulus, one tip 11 being axially displaced relative to the other tip 12 to produce a low pitch helix, much like lock washers now well known.

Differing from the well known washers just mentioned, the tip 11 of my washer is provided with an integral laterally-projecting tongue 13, the pointed tip 14 of which extends substantially tangential of the adjacent main body, with the tip of the tongue pointing away from the tip 11 by which it is carried. The tongue 13 is twisted or warped relative to the main body in a direction opposite to the pitch of the main body, i. e., in a direction toward the plane of the adjacent tip 12 with the lower edge of the sharpened tip 14 about in the plane of the lower edge of the adjacent tip 12.

In action, the structure is laid upon a foundation 15, around a threaded shank 16 with the tips 12 and 14 resting on the foundation and the inner extremity of the upper edge of tip 11 elevated above the plane of the upper surface of tip 12.

As a nut 17 is screwed to a seat, it engages the upper edge of the warped tip 11 and forces the same axially, at the same time forcing tip 14 into the foundation, the nut sliding somewhat readily over the upstanding tip 11 because the direction of rotative movement of the nut is away from the upper edge of tip 11.

Unscrewing movement of the nut is resisted by the friction of tip 11 thereon, induced by the axial stress under which it has been placed by the advanced nut and there is a tendency of the upper edge of the tip 11 to dig into the under face of the nut thus further resisting reverse movement of the nut. However, enforced reverse movement of the nut, even when embedment of tip 11 in the nut occurs, will cause the sharpened tip 14 to seat more firmly in the foundation so as to resist slipping of the washer on the foundation while ultimately permitting reverse movement of the nut relative to the washer.

I claim as my invention:

15 1. A lock-washer comprising a radially-split spring annulus of uniform thickness the substantially radial tips of which face each other and one tip being widened outwardly into an integral tongue projecting angularly outwardly away from the radially-outer ends of both of said tips, said widened tip being warped substantially about a radius of the annulus medially of the circumferential extent of the widened portion so as to project its radial end above the general plane of the annulus and the free end of the tongue below the general plane of the annulus, whereby the said widened tip and free tongue end may be simultaneously engaged by opposing clamping members.

20 2. A lock-washer comprising a radially-split spring annulus of uniform thickness the substantially radial tips of which face each other and one tip being widened outwardly into an integral tongue projecting angularly outwardly away from the radially-outer ends of both of said tips, said widened tip being warped substantially about a radius of the annulus medially of the circumferential extent of the widened portion so as to project its radial end above the general plane of the annulus and the free end of the tongue below the general plane of the annulus, whereby the said widened tip and free tongue end may be simultaneously engaged by opposing clamping members, the free end of the tongue being tapered to a point.

GEORGE TILLMAN SHELEY.
